(57) **CLAIM**

The ornamental design for an electric vacuum cleaner, as shown and described.

DESCRIPTION

FIG. 1 is a front perspective view of an electric vacuum cleaner showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a front perspective view thereof, showing a rechargeable battery and hose attached to the electric vacuum cleaner and the hose is in an extended state; and, FIG. 10 is a front perspective view of the electric vacuum cleaner thereof, showing a rechargeable battery and hose attached to the electric vacuum cleaner and the hose is in a stowed state.

The broken line showing of a rechargeable battery and hose in FIGS. 9 and 10 depicts environmental subject matter that forms no part of the claimed design. The remaining broken lines in the drawings depict portions of the electric vacuum cleaner that form no part of the claimed design.
